UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed July 25, 1922. Serial No. 577,359.

To all whom it may concern:

Be it known that I, MANSFIELD C. CRAWLEY, a citizen of the United States of America, and a resident of Groton, county of Tompkins, and State of New York, have invented certain new and useful Improvements in Typewriting Machines, of which the following is a full and clear specification.

The object of this invention is to provide a simple roller arrangement for clamping the sheet to the platen-roll in such manner as to smoothly and accurately feed the paper with the platen-roll, simple means being provided for throwing the rolls off and on, as more fully hereinafter set forth.

In the drawing—

Fig. 1 is a bottom view showing the rolls in the off position;

Fig. 2 is a similar view with the rolls in the on position;

Fig. 3 is a front view showing the rolls in working position;

Fig. 4 is a vertical sectional view showing the rolls in clamping relation to the work sheet on the platen;

Fig. 5 is a view similar to Fig. 4 showing the rolls in the off position;

Fig. 6 is a detail perspective view of one of the pairs of rolls;

Figs. 7 and 8 are views of details hereinafter described; and

Figs. 9 to 13 inclusive are views of additional details hereinafter described.

Referring to the drawings annexed by reference characters, 10 designates the platen roll journaled in the side plates 11 of a platen shift frame, these side plates being mounted on the forward ends of two pairs of parallel links 12 connected to the platen carriage at their rear ends. The numeral 13 designates the usual sheet metal paper-apron or guide extending around under the platen and provided with the usual openings for the under-side pressure rolls 14, said apron being rigidly connected to plates 11 by arms 43 and 44.

Connecting the side plates 11 is a rod 15 arranged under the platen and adapted to afford support for the pressure rollers and the throw-off bar hereinafter described. The rolls 14 are arranged in pairs, each roll having its pintles 16 resting in notches 17 formed in arms 18 pivotally mounted on the aforesaid rod 15. Each pair of arms 18 is connected by a bar 19, and each pair of roll-

supporting arms is normally pressed toward the platen surface by means of a coil spring 20, this spring surrounding the rod 15 at a point about midway between the arms 18 and having its two free end portions 20 hooked to the respective bars 19 to thereby uniformly press the two tandem rolls of each pair toward the platen.

Each of the arms 18, at a point under the rod 15, is provided with a depending hook-like cam lug 22, the lower hook part of each adjacent pair of lugs extending in opposite directions fore and aft of the machine and each having an upwardly-facing shoulder.

Supported on the shoulders of these hooks is a bar 23 extending transversely of the machine, the engagement with the bar being by means of a longitudinal cam slot 24 in the bar for each pair of hooks, each slot having a narrow portion at one end and a widened

portion at its other end, the walls of these two portions of the slot being parallel and connected by the inclined walls 24'. With this arrangement of slots, it will be seen that when the bar 23 is pushed in one direction

each pair of depending hooks will enter the narrow portions of the slots, and when the bar is pushed in the opposite direction these hooks will enter the wider portions of the slots.

When the hooks slide into the narrow portions of the slots, the hooks of each pair are brought into overlapped relation, thus

rotating the roller-carrying frames on the shaft 15 in a direction away from the platen, to thereby move the rolls to off position, as

shown in Figs. 2 and 5. When the bar is adjusted to bring the hooks into the wider portions of the slots, the hooks are allowed to spread apart, as shown in Fig. 4, sufficiently

to permit the springs 20 to force rolls 14 against the platen. In this simple manner, all the rolls may be quickly and simultaneously shifted to off or on position. As a simple means for reciprocating the bar 23

endwise transversely of the machine, I pivot

a bell-crank lever 25 at 45 on a lug 46 carried by one of the side plates 11, one end of this bell-crank being pivotally connected by

means of a screw pivot 26 to one end of the bar 23 and its other end having a slot 47 in

which engages the lower end of an upstanding finger lever 27, this finger lever being pivoted at 28 to the adjacent side plate 11.

By swinging the finger lever 27 forwardly the rolls 14 are thrown to off position, and by

swinging it backward the rolls are restored to working position. The rolls will remain in off position when lever 27 is moved forward and released, owing to the frictional engagement of hooks 22 with the oppositely-facing parallel faces of the narrow parts of the cam-slots 24, thereby avoiding the necessity of using extraneous locking means. It will be observed also that the hooks are 10 always in interlocking engagement with the actuator-bar 23 and, further, that the actuator-bar is practically entirely suspended on the hooks, the only additional support being the bell-crank 25 which affords a support 15 for one end of the bar. This construction contributes greatly to simplicity as well as certainty of operation.

A scale bar 29 is supported in front of the platen on the upper ends of a pair of arms 30 pivotally supported at their lower ends upon ears 31 extending forwardly from the side plates 11. The scale bar 29 is rigidly held to arms 30 and has its upper edge curved rearwardly so as to stiffen the same 25 and also form a housing for a series of sleeve-like metal rollers 32 rotatively mounted on a stationary rod 33 rigidly connecting the arms 30. A coil spring 34 normally tends to pull the upper ends of the arms 30 toward the platen to thereby keep the rolls 32 in working relation with the platen.

By swinging the scale bar 29 forwardly far enough to carry the coil springs 34 over the centers of the pivot screws 36 of the arms 30, the scale bar will come to rest at a considerable distance from the platen, as shown in dotted lines in Fig. 5, this position being maintained by reason of the contact of fingers 37, carried by the arms 30, with lugs 38 on the side plates 11. This far-off adjustment of the scale bar is desirable in making certain adjustments of the work sheets, but when it is desirable merely to throw the rolls 32 away from the platen 40 to release the work sheets this may be accomplished simultaneously with the throwing off of the under rolls 14, by interposing between the throw-off lever 27 and the adjacent side arm 30 a bar 39 slidably mounted 45 on two screws 40 tapped into the adjacent side plate 11. With this arrangement, when the throw-off lever is thrown forwardly to throw off the main rolls 14, the bar 39 will be pushed forwardly far enough to release 50 the front rolls 32, as shown in Figs. 5 and 9. In this case it will, of course, be understood that the springs 34 are not carried far enough forwardly to pass over the centers of the pivot screws 36, so that the springs 55 34 will tend to hold the arm 30 against the forward end of the bar 39. When lever 27 is thrown back to restore rolls 14 springs 34 will restore the rolls 32 and force slide 39 rearward at the same time.

60 Any suitable means may be employed for

70 preventing the roller-carrying arms 18 sliding on the rod 15, but I prefer to accomplish this purpose by striking up lugs 41 from the sheet metal paper apron 13, these lugs being positioned to slidably engage the side faces of the arms 18. It is desirable also to brace the long rod 33 with respect to the scale bar 29. For this purpose I fasten to the rod, at suitable intervals, small sheet metal brackets 42, as shown in Figs. 11 and 75 13, and shape the upper and rear edges of these brackets to abut against the inner curved face of the bent scale bar. To fasten these bracing brackets to the rod I provide each with a rounded notch in which 80 the shaft fits, and crimp the brackets rigidly upon the shaft. The channel scale bar 29 is mounted on the arms 30, a desirable way of doing this being to make the arms and the scale bar of sheet metal and form them 85 integral, the arms being formed on the ends of the bar and bent so as to lie at right angles to the bar.

What I claim is:

1. A paper-feeding mechanism for typewriting machines consisting of pairs of roll-carrying pivoted arms each having a depending hook-lug, a spring for each pair of arms adapted to normally force the rolls toward the platen, a bar and means for shifting it longitudinally of the platen, said bar being provided with a plurality of longitudinal cam-slots each of which is wider at one end than at the other and each of which engages a pair of hooks on the 100 roll-carrying arms.

2. In combination with a typewriting machine, a paper-feeding mechanism embodying a plurality of pairs of roll-carrying arms, depending lugs carried by these arms, springs for normally swinging the roll-carrying ends of the arms toward the platen, and a reciprocable bar for simultaneously actuating said lugs, said bar being supported on said lugs. 105

3. A paper-feed mechanism for platens consisting of a rod supported below the platen, roll-carrying arms pivotally mounted on said rod, spring means for forcing said roll-carrying arms toward the platen, each of said arms being provided with a depending hook having an upwardly-facing shoulder, a reciprocable bar provided with a cam-slot for each pair of said hooks, said bar being supported on said shoulders. 115

4. In a paper-feed for roll-platens, a plurality of roll-carrying frames and means for normally pressing them toward the platen, each of said frames being provided with a cam-lug, and a reciprocable bar provided with longitudinal cam-slots for interlocking engagement with said lugs to forcibly withdraw the rolls from the platen. 125

5. In a typewriting machine, a paper feed mechanism embodying a series of under rolls 120

- and means for throwing them off and on embodying an upstanding lever, a front roll structure pivoted to swing back and forth with respect to the platen, and means interposed between said throw-off lever and said front roll structure to cause the front rolls to be thrown off when said lever is actuated to throw off the under rolls, said means consisting of a fore-and-aft slidable bar mounted on one of the side-plates of the platen frame and having abutting relation at one end with said upstanding lever and abutting relation at the other end with said front roll structure. 50
- 15 6. In a typewriting machine, a paper feed mechanism embodying a series of under rolls and means for throwing them off and on embodying an upstanding lever, a front roll structure pivoted to swing back and forth 55 with respect to the platen, and means interposed between said throw-off lever and said front roll structure to cause the front rolls to be thrown off when said lever is actuated to throw off the under rolls, said means embodying a slidable bar mounted on the platen frame. 60
- 15 7. In a paper feed mechanism for typewriting machines, a front feed roll structure embodying a pair of arms pivoted in a platen frame, a rod connecting these arms, a channel scale bar mounted on the arms, a series of rolls mounted on the rod, and a series of bracing brackets affixed to the rod and abutting the inner face of the scale bar. 70
- 35 8. In a typewriting machine, a platen frame carrying a roll-platen, a rod mounted on said frame and extending along underneath the platen, a plurality of feed-rolls mounted on arms pivoted on said rod, spring means for normally swinging said roll-carrying arms toward the platen, means for forcibly swinging said feed-rolls away from the platen and holding them away, this latter means embodying lugs projecting 80 from said roll-carrying arms, a reciprocable bar lying parallel with the aforesaid rod and provided with cam-faces for engagement with said lugs, some of said cam-faces 85 being arranged to face rearwardly and the other cam-faces being arranged to face forwardly, and devices for endwisely reciprocating said bar. 90
9. A paper feed mechanism for typewriting machines embodying a front roll structure consisting of a pair of arms pivotally mounted on the platen frame, a scale bar connecting said arms and formed integral therewith, the upper edge of said scale bar being bent rearwardly to form a housing and a rod connecting said arms and carrying rolls lying within said housing. 95
10. In a paper-feed for roll-platens, a plurality of roll-carrying frames and means for normally pressing them toward the platen, each of said frames being provided with a cam-lug, and a reciprocable bar provided with longitudinal cam-slots for engaging said lugs to forcibly withdraw the rolls from the platen, said cam-slots each consisting of two parts one narrower than the other, the walls of the narrower part being so shaped as to frictionally hold the cam-lugs when they are forced into said narrower part and thus lock the rolls in off position. 100
11. In a typewriting machine, a platen roll and frame, forwardly-extending and rearwardly-extending feed-roll-carrying pivoted arms and spring means for normally forcing the roll-carrying ends of the arms toward the platen, cam-lugs projecting from both sets of arms, and means for swinging the roll-carrying ends of the arms away from the platen through the medium of said cam-lugs against the action of said spring means, embodying a bar lying under the platen-roll and parallel therewith and adapted to be endwisely shifted, said bar being provided with pairs of oppositely-facing cam-faces positioned to engage and swing the lugs carried by the forwardly-extending roll-carrying arms in one direction and the lugs carried by the other set of roll-carrying arms in the opposite direction. 105

In testimony whereof, I hereunto affix my signature.

MANSFIELD C. CRAWLEY.
